HYDROMETRIC INSTRUMENT

Nicholas Chuy, Leavenworth, Kans., assignor of
one-half to Herbert Tsai, Chicago, Ill.

Application March 31, 1938, Serial No. 199,231

3 Claims. (Cl. 265—45)

This invention relates to a hydrometric instrument or means for association with the water cooling system of an internal combustion engine so as to determine the specific gravity of the cooling liquid when it contains alcohol or other anti-freezing agent.

It is further aimed to provide such a means as forms a permanent part for attachment on the automobile, vessel or other vehicle, to enable one to observe the specific gravity at a glance and constantly.

The more specific objects and advantages will become apparent from a consideration of the description following taken in connection with accompanying drawings illustrating an operative embodiment.

In said drawings:

Figure 1 is a view showing my improvements in connection with a fragment of an automobile engine and the instrument board;

Figure 2 is a front elevation of the instrument board and parts mounted thereon;

Figure 3 is a front elevation looking toward the instrument board, with the condenser mounted in a modified manner;

Figure 4 is a view looking toward an automobile instrument panel, where the hydrometric device is located behind the same;

Figure 5 is an enlarged substantially longitudinal sectional view of the device which is attached to the cylinder head;

Figure 6 is a substantially central vertical sectional view taken on the line 6—6 of Figure 1;

Figure 7 is a detail section taken on the line 7—7 of Figure 6;

Figure 8 is a horizontal sectional view taken on the line 8—8 of Figure 6, and

Figure 9 is a detail of the mounting or connection of the device of Figure 1 to the instrument board.

Referring specifically to the drawings wherein like reference characters designate like or similar parts, an opening is drilled and tapped at 10 in the cylinder head 11 of an internal combustion engine having a water cooling system, the engine for instance being a propelling engine of an automobile or other self-propelled vehicle, the propelling engine of a vessel, or even a stationary engine. The invention is for use where the vehicle is used in climates wherein the cooling water is apt to freeze and requires the use of alcohol and other anti-freezing liquids or media therein, to keep the engine in an operative condition.

Into the said tapped opening 10, a plug 12 is screw threaded as shown, being vertically dis-

posed. The plug is generally cylindrical and hollow, having a central tubular member 13 detachably screw threaded therein as at 14. Detachably screw threaded at the lower extremity of the plug 12 is a closure 15, at 16, the closure forming a seat 17 for an inverted conical valve 18 having a guide stem 19 which extends loosely into the bore or passageway 20 of the tube 13.

At the upper end of the tube 13, a seat 21 is provided for a check valve 22 which tends to close the passage 20. Threaded to the tube 13 as at 23 is a cap 24 from which an outlet tube or pipe 25 leads to a cylinder or container 26 of a hydrometric device 27. The pipe 25 discharges into the container 26 at a predetermined level and from the same level, a return pipe 28 leads to the radiator of the internal combustion engine.

In the operation of the automobile or vehicle, the engine will circulate the water containing the anti-freeze in its cooling system, and upon heating thereof to a predetermined extent, the consequent pressure will cause the valve 18 to open and the space within plug 12 to fill with the cooling fluid, that is mixture of water and anti-freeze, the weight of which will thereafter cause the valve 18 to lower and seat. A quantity of the fluid trapped in the plug 12 due to the further heating and pressure within the plug 12, will be forced through the bore 20, past the valve 22 and through the pipe 25 into the container 26, maintaining a level at the inlet of the pipe 25 and the outlet of the pipe 28, the surplus being returned to the radiator.

Operating freely within the container 26 is a hydrometric bulb or float of conventional form designated 29, and the movement of which is subject to the specific gravity of the fluid in the container. L-shaped guide members 30 are rigidly connected to the hydrometer bulb 29 and such members extend through brackets 31 on the interior of the container, being slideable therein to restrain the movement of the hydrometer bulb to sliding without rotation.

Peripherally of the hydrometer bulb, a spiral groove 32 is provided which is entered by a projection 33 of a floating indicator ring 34. The periphery of the ring 34 is suitably calibrated as shown, so that the calibration corresponding to the specific gravity of the fluid within the container will register with a glass covered window 35 in the wall of the container 26.

As the engine operates, the passage of the fluid from the plug 12 or cooling system of the engine, will be practically continuous through the plug, bore 20, pipe 25 and container 26, with the over-

flow returning through the pipe 28 to the radiator of the automobile. According to the specific gravity of such fluid, the portion thereof within the container will cause the hydrometric 5 float 29 to rise or fall, such rising or falling being without turning due to the connections at 30-31. Such rectilinear movement of the hydrometric bulb 29 however due to the co-action of the lug 33 and groove 32, will rotate the indicator float 10 34 in the proper direction, while such float floats on the fluid in the container, indicating at its calibration in registry with window 35, the specific gravity of the fluid within the cooling system of the engine, thus apprising the operator for 15 guidance in replenishing or adding to the supply of anti-freeze within the cooling system. Float 29 has a guide rod 46 thereon associated with an opening 47 in the top of the container 27.

As shown in Figures 1 and 9, the hydrometric 20 device 27 is preferably located on the instrument board 40 of the automobile, resting on a bracket 41 fastened thereto, the pipes 25 and 28 being better connected to the instrument board 40 by means of a plate 42, connecting them, and a screw 25 43 which is threaded therethrough and binds against the instrument board. Also, in the pipe 28 between the hydrometric device and radiator, a condenser of any suitable form as at 44 may be provided, the condenser serving to condense any 30 of the fluid which may be in a vaporous state, to prevent liberation thereof into the atmosphere at the radiator.

As shown in Figure 3, the condenser which is here designated 44', may be mounted directly on 35 the instrument board here designated 40'.

As shown in Figure 4, the hydrometric device here designated 27' may be mounted behind the instrument board here designated 40'', with its

window such as 35 in registry with a window of transparent material at 45 in the instrument board and through which the calibrations of the float 34 may be observed.

Various changes may be resorted to provided 5 they fall within the spirit and scope of the invention.

I claim as my invention:

1. An hydrometric device comprising a container for fluid, an hydrometer tube in the fluid, 10 means constraining the hydrometer tube to travel in a rectilinear path, an indicator float on the fluid, and a pin and spiral groove connection between the tube and float to actuate the float as an indicator according to the specific gravity of 15 the fluid.

2. An hydrometric device comprising a container for fluid, an hydrometer tube in the fluid, means constraining the hydrometer tube to travel in a rectilinear path, an indicator float on the 20 fluid, a pin and spiral groove connection between the tube and float to actuate the float as an indicator according to the specific gravity of the fluid, the first mentioned means comprising arms on the hydrometer bulb, and brackets with- 25 in the container engaged by said arms, a rod rising from the hydrometer float, and the container having a top member provided with an opening engaged by the rod, and an inlet and an outlet for said container.

3. An hydrometric device comprising a container for fluid, an hydrometer tube in the fluid, means constraining the hydrometer tube to travel in a rectilinear path, an indicator float on the fluid, and an operative connection between the 35 tube and float to actuate the float as an indicator according to the specific gravity of the fluid.

NICHOLAS CHUY.
